UNITED STATES PATENT OFFICE

2,583,501

SWIVEL PIN MOUNTING FOR PLANER APRONS

John M. Walter, Cincinnati, Ohio, assignor to
The G. A. Gray Company, Cincinnati, Ohio, a
corporation of Ohio

Application December 17, 1946, Serial No. 716,731

3 Claims. (Cl. 99—52)

1

My invention relates to a new development in connection with the swivel pin mounting of planer aprons. The conventional planer carries the apron, on which the cutting tools are to be mounted, on a pivotal mounting in what is known as the tool box, the latter being carried on the planer head, and the head in turn mounted on the planer cross rail.

The firmness of the apron against vibration or play is an important feature in accurate work in metal planers. In general practice the tool box is provided with two projecting side walls which define between them, a space into which the apron hangs, which is known as a jaw or pocket. The apron can be and is swung outwardly from this jaw so as to clear the tools from the work on a return stroke. On the work stroke the apron rests firmly against the face of the tool box lying between the two side walls of the box. To pivot the apron, bosses are provided at the upper ends of the side walls, and a slightly tapered hole is formed in the tool box and the bosses. The pin is held in the bosses and passes through the hole in the top of the apron.

When this pin becomes worn it can be adjusted somewhat because of its tapered construction, but this has not, over the years, proven to be fully satisfactory. When the pin wears out, and replacement is necessary, it is often the case that the entire structure must be bored out again in fitting the new pin. Finally the movement of the apron on a tapered pin is not one which assures the best fit of the apron between the side walls of the tool box jaw.

According to my invention a perfectly cylindrical pin is used, and means provided which can be replaced for assuring a perfect fit of the pin, not only in the tool box but in the apron as well. One of my objects is to provide a pin which has a uniform dimension at all bearing surfaces, thus avoiding making holes of different diameters in the bosses of the tool box and the top of the apron. It would be possible but very difficult to make holes of different diameter but yet perfectly centered on each other. This difficulty would be an obstacle to remachining the parts to take a new pin. By using a series of holes of precisely the same diameter, I am able to form the holes by retaining the apron and tool box in a fixture and boring the holes at one time through both members. They are thus perfectly aligned. I then use bushings as bearing elements between the pin and the bosses and apron, with the advantage of being able to replace the bushings in case of wear, thus insuring

2

perfectly aligned holes through the parts at all times.

I have shown one example of my invention in the appended drawings, and wish it understood that this is an example only, and that modifications without departing from the principles of the structure as set forth in the appended claims, are within the scope of my invention.

In the drawings:

10 Figure 1 is a front elevation of a tool box and apron.

Figure 2 is a side view thereof.

Figure 3 is a section on the line 3—3 of Figure 2.

15 I have illustrated a tool box having a main body 1, with side walls 2, 2, forming the pocket or jaw in which the apron 3 is held during cutting movement. On the face of the apron I have shown a tool 4 held by clamps 5.

20 In building my construction the apron and tool box are assembled together in proper position and held firmly. Thereupon a cylindrical hole is bored straight through the upper ends of the side walls (forming bosses) and through the top of the apron. I have indicated this hole at 2a, 2a in the side walls of the tool box and at 3a in the apron.

25 Bushings 6 are provided, which in this case are alike, and they are pressed lightly into the holes 2a, 2a, and into the ends of the holes 3a. Over the open ends of the bosses I mount thrust plates 7. The pin 8 is thrust through the assembly, and is machined to have a floating fit in the bushings.

30 For lubrication purposes it is desired to machine away a zone of the pin as at 8a, between the ends of the two bushings in the ends of the apron hole, thus leaving a space between the pin and the hole, which is intercepted by an oil hole 9 in the top of the apron.

35 Now it would be possible to press the pin into the holes 2a, 2a and have bushing only in the apron. It would also be possible to press the pin into the hole in the apron and have bushing only in the tool box, but either of these constructions would require either two working diameters on the pin or two working diameters of holes, and as has already been remarked, it is difficult to align perfectly, holes of different diameters,

40 which also applies to surfaces of different diameters. By my invention the hole is bored at once through the apron and tool box, and the pin is cylindrical and has but one single working diameter, although certain advantages of my inven-

tion would apply if different sized holes were bored.

My invention would still apply if the bushings were tightly driven in, or if the pin fitted tightly in the bushing of one of the elements, but by the particular arrangement the friction developed in the pivotal arrangement is minimized by lightly pressing in the bushings and having a floating fit of the pin restrained by end plates.

Certain of the advantages of my construction may be obtained by boring the hole as already described, and omitting the bushings, permitting the pin, which is straight cylindrical, as before to float in the assembly. When this is followed, the replacement by bushings is not available in connection with repair of a worn construction, and a new pin and newly bored out holes would be required.

Having thus described my invention, what I claim as new and desire to secure by Letters Patent is:

1. In combination with a tool box and apron, a straight cylindrical pin of uniform diameter for pivotally mounting the apron on the tool box, said apron and tool box having mounting holes for said pin bored therethrough in alignment and of uniform cylindrical diameter throughout, and bushings for said pin in the holes in said tool box, and within the ends, at least, of the hole in the apron.

2. The combination of claim 1 in which said bushings are lightly pressed into the holes in the tool box, and lightly pressed into the ends at least

of the hole in the apron, said bushings being of like diameter, said pin being floatingly held in said bushings, and end restraining means for holding the pin in place, said means comprising end plates located to close the holes in the tool box.

3. In combination with a tool box and apron, pin bosses in the tool box, said apron and pin bosses having holes bored therethrough in alignment, a pin passing through the holes, and bushings located within the holes and constituting the bearing on the pin, said bushings being replaceable, the said pin being floatingly mounted in the bushings, and means for restraining endwise movement of the pin in the bushings.
